PACKING TRAY

Paul D. Friday, 4480 SW. Laurelwood Drive,
Portland, Oreg. 97225

Filed Feb. 1, 1966, Ser. No. 869

Term of patent 14 years

(Cl. D58—13)

Fig. 3

Fig. 4

Fig. 5

FIGURE 1 is a perspective view of a packing tray, showing my new design.

FIGURE 2 is a sectional view taken on the line 2—2 in FIGURE 1.

FIGURE 3 is a bottom plan view of the packing tray.

FIGURE 4 is a side elevational view, the opposite side being identical.

FIGURE 5 is an end elevational view of the tray, the opposite end being identical.

I claim:

The ornamental design for a packing tray, substantially as shown and described.
